[57] ABSTRACT

A device for controlling a mechanism which is adapted to interrupt the electrical heating circuit of a kiln; the mechanism being of the type which includes a pivotally mounted rod having the inner end thereof extending into a kiln and being operative upon downward movement of said inner end to interrupt the electrical heating circuit of the kiln. The device is a fusible pyrometric member adapted to be held in the path of downward movement of the inner rod end to prevent such movement until the interior of the kiln has been exposed to a predetermined amount of heating. The member has means, such as a uniform transverse cross-section or a notch in which the inner rod end is engageable, to accurately regulate the amount of heating required to cause deformation of the member.

DEVICE FOR CONTROLLING A KILN SHUT-OFF MECHANISM

BACKGROUND OF THE INVENTION

1. Field of the Invention

This invention relates to mechanisms for automatically interrupting the electrical heating circuit of a kiln, and specifically to an improved device for controlling such mechanisms.

2. Description of the Prior Art

Ceramic artists and hobbyists commonly use pyrometric cones for controlling the firing of ceramic products in a kiln. Such cones are composed of fusible ceramic material, and upon exposure to a predetermined amount of heating partially liquefy and deform, thus providing a visual indication of the completion of firing. The operator, upon observing deformation of the cone, manually interrupts the electrical heating circuit of the kiln. This method for controlling the firing of ceramic products, while operable, requires that the operator observe the interior of the kiln continuously during the critical period near the end of firing. Moreover, due to the intense heat generated within the kiln, accurate observation of cone deformation is often precluded.

Shut-off mechanisms have been developed for automatically interrupting the electrical heating circuit of a kiln after the interior of the kiln has been exposed to a predetermined amount of heating, i.e., upon completion of firing. Mechanisms of this type are disclosed in Dawson U.S. Pat. Nos. 2,675,600 and 3,287,530. Such mechanisms employ a mechanical system of rods, levers and switches, and a heat sensitive element for controlling the movement of the various elements comprising the system. The heat sensitive element generally is a conventional pyrometric cone which is positioned in the path of movement of one of the elements of the system, usually an end of a pivotally mounted rod, to prevent movement of such element until the interior of the kiln has been exposed to a predetermined amount of heating. The principal reason for employing pyrometric cones as the heat sensitive control element in kiln shut-off mechanisms is because such cones are sensitive not only to temperature but also to time of exposure; the combined effect of these parameters generally being referred to as the amount of heating. Thus, since ceramic products also are sensitive to temperature and time of exposure, and consequently the firing thereof is a function of amount of heating, pyrometric cones provide definite advantages over pyrometers and like devices which are sensitive to temperature only for controlling kiln shut-off mechanisms.

Several problems, however, attend the use of conventional pyrometric cones as the heat sensitive control element in kiln shut-off mechanisms. Conventional pyrometric cones generally are shaped as truncated triangular pyramids, having three longitudinally extending, tapered sides. As used in kiln shut-off mechanisms, a cone is held by two horizontally extending supporting strips which contact one of the longitudinally extending sides of the cone near the top and bottom thereof. One end of a downwardly biased rod, comprising one of the elements of the mechanical system of the shut-off mechanism, generally engages the central portion of the edge of the cone opposite the side thereof contacted by the supporting strips. Upon exposure of the interior of the kiln to a predetermined amount of heat-

ing, the cone partially liquefies and deforms, permitting the rod end to move downwardly and initiate the movements of the various elements comprising the mechanical system.

- 5 Due to the relatively small cross-sectional area of the cone near the top thereof, the transverse bending force applied to the cone by the rod end can result in premature deformation or even fracturing of the cone. Also, and perhaps more significantly, since the transverse 10 cross-sectional area of the cone varies continuously from the bottom to the top thereof, lateral placement of the cone on the supporting strips is critical for achieving the desired firing. For example, it has been found that lateral displacement of the cone by as little 15 as one-eighth inch can result in maximum firing temperature variations of as much as 10°F. Thus, the artist or hobbyist must position the cone very carefully on the supporting strips if under- or over-firing is to be avoided.
- 20 A further difficulty in the use of conventional pyrometric cones in kiln shut-off mechanisms derives from the fact that the cones are composed of fusible ceramic material which liquefies when exposed to a predetermined amount of heating. Such liquefaction can result 25 in adherence of the liquefied materials to the elements of the shut-off mechanism which contact the cone, i.e., the supporting strips and rod end.

SUMMARY OF THE INVENTION

- 30 The device of the present invention obviates the problems described above with respect to the use of conventional pyrometric cones as the heat sensitive control element for kiln shut-off mechanisms. The device of the invention is adapted to be used for controlling kiln shut-off mechanisms of the type which include a rod adapted to extend through a wall of a kiln with the inner end thereof extending into the kiln and the outer end thereof extending out of the kiln, mounting means pivotally supporting the rod intermediate said ends, biasing means urging the inner rod end downwardly, supporting means positioned below the inner rod end for holding the device of the invention in the path of downward movement of said inner end, retaining means attached to the outer rod end, actuating means engageable by the retaining means when the device prevents downward movement of the inner rod end and releasable by the retaining means when the device permits downward movement of said inner end, and a switch contactable by the actuating means for interrupting the electrical heating circuit of the kiln when the actuating means is released by the retaining means. Basically described, the device comprises, a pyrometric member composed of fusible ceramic material and having means for accurately regulating the amount of heating required to cause deformation of the member so that upon exposure of the member to said amount of heating, the member will at least partially liquefy and deform, permitting the inner rod end to move downwardly under the influence of the biasing means, thereby causing the electrical heating circuit of the kiln to be interrupted.
- 35 40 45 50 55 60 65

The regulating means may be comprised by the pyrometric member having a uniform transverse cross-section so that irrespective of the lateral placement of the member on the supporting means of the shut-off mechanism, the member will deform upon exposure to a predetermined amount of heating.

The regulating means also may be comprised by one or more transversely extending notches in the pyrometric member which are adapted to engage the inner end of the shut-off mechanism rod. The notch or notches eliminate errors in the lateral placement of the member with respect to the supporting means and inner rod end. Moreover, by employing a plurality of such notches controlled variations in the amount of heating required to cause deformation of the member may be achieved utilizing a particular ceramic material and member configuration.

The transverse cross-sectional area of all embodiments of the pyrometric member is large enough to eliminate premature deformation of the members.

Also, preferably, the portions of the member which contact the supporting means and inner rod end of the shut-off mechanism are coated with a refractory material to prevent adherence of the ceramic material to the elements of the shut-off mechanism when the member liquifies upon exposure to heating.

With the foregoing in mind, it is a primary object of the present invention to provide an improved device for controlling a mechanism adapted to interrupt the electrical heating circuit of a kiln.

It is also an object of the invention to provide a device as described in the preceding object, which device comprises a pyrometric member composed of fusible ceramic material.

It is an additional object of the invention to provide a device as described in the preceding object, wherein the member has means for accurately regulating the amount of heating required to cause deformation of the member.

It is a further object of the invention to provide a device as described in the preceding objects, which device is both easy to use and reliable.

These and other objects of the invention will become apparent upon a consideration of the detailed description of the preferred embodiments thereof given in connection with the following drawings, wherein like reference numerals identify like elements throughout.

BRIEF DESCRIPTION OF THE DRAWINGS

FIG. 1 is a perspective view of a typical kiln shut-off mechanism in which the device of the invention is adapted to be employed;

FIG. 2 is a perspective view of a first embodiment of the device of the invention;

FIG. 3 is a sectional view taken on line 3 — 3 of FIG. 2;

FIG. 4 is a perspective view of a second embodiment of the device of the invention;

FIG. 5 is a perspective view of a third embodiment of the device of the invention; and

FIG. 6 is an elevational view of a fourth embodiment of the device of the invention.

DESCRIPTION OF THE PREFERRED EMBODIMENTS

A typical kiln shut-off mechanism is shown in FIG. 1, as designated by reference numeral 10. Mechanism 10 is of the type described in Dawson U.S. Pat. No. 2,675,600, and generally includes a rod 12 adapted to extend through a wall of a kiln. Within the kiln wall, rod 12 is surrounded by a sleeve 14 having a plate 16 affixed to the inner end thereof, and a plate 18 affixed

to the outer end thereof. Plates 16 and 18 abut the inner and outer surfaces, respectively, of the kiln wall. The inner end of rod 12 extends inwardly into the kiln beyond plate 16, and the outer end of the rod extends outwardly out of the kiln beyond plate 18.

Mechanism 10 includes mounting means for pivotally supporting rod 12 intermediate the inner and outer ends thereof. The mounting means conveniently comprises a coupler assembly 20 affixed to plate 18. Biasing means are provided for urging the inner end of rod 12 downwardly. The biasing means conveniently comprises a weight 22 affixed to rod 12 near the inner end thereof. Supporting means are attached to plate 16 and positioned below the inner end of rod 12 for holding the device of the invention in the path of downward movement of the inner rod end. The supporting means conveniently comprises a pair of horizontally separated, horizontally extending strips 24, only one of which is shown in the drawing. A retaining means, such as a collar assembly 26, is attached to the outer end of rod 12.

A housing 28 is affixed to plate 18, and an actuating means is operatively connected to the outer surface of the housing. The actuating means conveniently comprises a pivotally mounted weighted arm assembly 30. Arm assembly 30 includes an adjustably mounted plate 32 which is engageable by collar assembly 26 when the device of the invention prevents the inner end of arm 12 from moving downwardly, and which is releasable by collar assembly 26 when the device of the invention permits the inner end of arm 12 to move downwardly. Integrally affixed to the lower portion of arm assembly 30 is a projection 34. When plate 32 is released by collar assembly 26, arm assembly 30 pivots downwardly, so that projection 34 enters an opening 36 formed in the outer surface of housing 28. Mounted within housing 28 is a switch (not shown) that is contactable by projection 34 for interrupting the electrical heating circuit of the kiln. As will be apparent from this brief description, the movements of the various mechanical elements comprising mechanism 10 are initiated by downward movement of the inner end of rod 12, and the latter movement is controlled by the device of the invention. A detailed description of the structure and operation of mechanism 10 appears in the aforementioned Dawson patent.

A first embodiment of the device of the invention is shown in FIGS. 1 — 3, and comprises a pyrometric member 40 composed of fusible ceramic material. Member 40 is generally configured as a truncated rectangular pyramid having four longitudinally extending planar sides which taper inwardly from one end (the left end as seen in FIG. 2) to the other end (the right end as seen in FIG. 2) thereof. One of the sides of the member is adapted to contact strips 24 of mechanism 10 so that the member will be held in the path of downward movement of the inner end of rod 12.

Member 40 has means for accurately regulating the amount of heat required to cause deformation of the member. Such means are comprised by a plurality of transversely extending notches 42 in the side of member 40 opposite the side thereof adapted to be contacted by strips 24. Notches 42 extend entirely across the side of member 40, and when the member is held on strips 24, the inner end of rod 12 is engageable in one of the notches. Thus, lateral placement of member

40 with respect to strips 24 and the inner end of rod 12 is accurately controlled by notches 42.

In operation, member 40 prevents downward movement of the inner end of rod 12 until the interior of the kiln has been exposed to a predetermined amount of heating. During heating, member 40 partially liquefies until the downward bending force applied to the member by the inner end of rod 12 causes the member to deform, thus permitting the inner rod end to move downwardly to initiate the hereinabove described movements of the mechanical elements comprising mechanism 10.

The transverse cross-sectional area of member 40 is large enough to preclude premature deformation or fracture of the member, as frequently occurs with conventional pyrometric cones.

Also, preferably, notches 42 and the portions of the side of member 40 which contact strips 24, such portions being designated by reference numeral 44, are coated with a refractory material, such as high alumina, zirconia or platinum, to prevent the ceramic material from which member 40 is composed from adhering to the inner end of rod 12 or strips 24 when the ceramic material liquefies during heating.

Member 40 may be composed of various ceramic materials or mixtures of such materials to provide the desired deformation characteristics. Also, notches 42 permit controlled variations in the amount of heating which may be achieved utilizing a member of a particular composition and configuration.

A second embodiment of the device of the invention is shown in FIG. 4, and comprises a pyrometric member 50 composed of fusible ceramic material. Member 50 has one longitudinally extending planar side 52 which is adapted to contact strips 24. The portions of the exterior surface of member 50 other than side 52 are generally arcuately shaped. Other than differences in configuration, members 40 and 50 are identical.

A third embodiment of the device of the invention is shown in FIG. 5, and comprises a pyrometric member 60 composed of fusible ceramic material. Member 60 has a uniform rectangular transverse cross-section defined by four longitudinally extending planar sides so that irrespective of the lateral placement of the member on strips 24, a predetermined amount of heating will be required to cause deformation of the member. If desired, however, member 60 may have a transversely extending notch 62 in one side thereof to facilitate placement of the member on strips 24. Also, if desired, notch 62 and the portions of the side of member 60 adapted to contact strips 24 may be coated with a refractory material to prevent the ceramic material from which the member is composed from adhering to the elements of mechanism 10 upon liquefaction of the ceramic material.

A fourth embodiment of the device of the invention is shown in FIG. 6, and comprises a pyrometric member 70 composed of fusible ceramic material. Member 70 is generally configured as a truncated rectangular pyramid similar to member 40 described above. Alternatively, member 70 may be configured as a truncated wedge having four longitudinally extending planar sides of which two opposite sides are tapered inwardly from one end (the left end as seen in FIG. 6) to the other end (the right end as seen in FIG. 6) thereof.

The means for accurately regulating the amount of heating required to cause deformation of member 70

are comprised by a transversely extending notch 72 in one side of the member and a transversely extending notch 74 in the opposite side of the member. Member 70 may be placed on strips 24 with either notch 72 or notch 74 facing upwardly to engage the inner end of rod 12. The transverse cross-sectional area of member 70 at the longitudinal position of notch 74 is less than the transverse cross-sectional area of the member at the longitudinal position of notch 72. Therefore, a greater amount of heating will be required to cause deformation of the member when the inner end of rod 12 is engaged by notch 72 than when the inner end of the rod is engaged by notch 74. However, the amount of heating required to cause deformation of the member when the inner rod end is engaged by either notch is accurately regulated due to the predetermined placement of the notches. When the inner rod end is engaged by notch 72, strips 24 are contacted by notch 74 and a portion of the side of member 70 having notch 74 therein. Similarly, when the inner rod is engaged by notch 74, strips 24 are contacted by notch 72 and a portion of the side of the member 70 having notch 72 therein. Preferably, notches 72 and 74 and the portions of the sides of the member which are adapted to contact strips 24, such portions being designated by reference numeral 76, are coated with a refractory material to prevent the ceramic material from which member 70 is composed from adhering to the elements of mechanism 10 when the ceramic material fuses.

As will be apparent, all of the embodiments of the device of the invention are used in the manner described above with respect to member 40. As will also be apparent, each embodiment of the device of the invention has means, such as a uniform transverse cross-section or transversely extending notches, for accurately regulating the amount of heating required to cause deformation of the member comprising the device.

Configurations other than those of members 40, 50, 60 and 70 also may be employed in the device of the invention. For example, the member may have a circular, semi-circular or semi-elliptical transverse cross-section.

From the foregoing description, it will be apparent that the device of the invention obviates the problems associated with the use of conventional pyrometric cones in kiln shut-off mechanisms. The tedious task of accurate lateral placement of such cones to achieve the desired firing characteristics is eliminated. Also, the device of the invention is not subject to premature deformation or fracture. In addition, adherence of liquefied ceramic material to the elements of the shut-off mechanism which contact the device is eliminated.

While the foregoing constitutes a detailed description of the preferred embodiments of the invention, it is recognized that various modifications thereof will occur to those skilled in the art. Therefore, the scope of the invention is to be limited solely by the scope of the appended claims.

I claim:

1. A device for controlling a mechanism adapted to interrupt the electrical heating circuit of a kiln, said mechanism being of the type including a rod adapted to extend through a wall of a kiln with the inner end thereof extending into the kiln and the outer end thereof extending out of the kiln, mounting means pivotally supporting the rod intermediate said ends, biasing means urging said inner end downwardly, support-

ing means positioned below said inner end for holding said device in the path of downward movement of said inner end, retaining means attached to said outer end, actuating means engageable by said retaining means when said device prevents downward movement of said inner end and releasable by said retaining means when said device permits downward movement of said inner end, and a switch contactable by said actuating means for interrupting the electrical heating circuit of the kiln when said actuating means is released by said retaining means, said device comprising:

a pyrometric member composed of fusible ceramic material and having means for accurately regulating the amount of heating required to cause deformation of the member so that upon exposure of the member to said amount of heating, the member will at least partially liquefy and deform, permitting said inner end to move downwardly under the influence of said biasing means, thereby causing said electrical heating circuit to be interrupted, said regulating means comprising at least one transversely extending notch in at least one side of said member, said notch extending entirely across said one side, and said member having a planar side thereof opposite said one side and contactable with said supporting means, said inner end being engageable by said notch to accurately control the

placement of the member with respect to said supporting means and inner end.

2. A device as recited in claim 1; wherein the transverse cross-sectional area of said member varies longitudinally of the member; and wherein each of two opposite sides of said member have at least one of said notches therein and the notch in one of said sides is longitudinally displaced with respect to the notch in the other of said sides so that when said inner end is engaged by one of the notches a different amount of heating will be required to cause deformation of the member than when said inner end is engaged by the other of said notches.

3. A device as recited in claim 1, wherein the portions of said member adapted to contact said supporting means and said notch are coated with a refractory material to prevent said ceramic material from adhering to said supporting means and inner end when the ceramic material liquefies during heating.

4. A device as recited in claim 1, wherein said member has a rectangularly shaped transverse cross-section.

5. A device as recited in claim 1, wherein said member has at least a partially arcuately shaped transverse cross-section.
